United States Patent Office.

GEORGE A. JONES, OF NEW YORK, N. Y.

Letters Patent No. 74,695, dated February 18, 1868.

IMPROVEMENT IN TRAINS FOR LAMPS.

The Schedule referred to in these Letters Patent and making part of the same.

TO ALL WHOM IT MAY CONCERN:

Be it known that I, GEORGE A. JONES, of the city of New York, in the county of New York, and State of New York, have invented certain new and useful Improvements in Mechanical Movements or Trains for Lamps; and I do hereby declare that the following is a full, clear, and exact description thereof, and of their mode or manner of operation, reference being had to the accompanying drawings, and to the letters of reference marked thereon, and making a part of this specification.

My invention has reference more particularly to the trains or mechanical movements used in such lamps as are the subject-matter of Letters Patent of the United States, granted February 10, 1863, to F. B. Caravan, and which are intended to burn kerosene and oils rich in carbon, and in which the mechanism is used to force up to the wick an increased supply of atmospheric air, and consists in such improvements in the construction and arrangement of different parts of the mechanism as greatly reduces the cost of construction of such mechanism without impairing its efficiency.

Figures 1 and 2 are representations of the opposite side plates sustaining the mechanism.

Figures 3 and 4 are perspective views of the mechanism from opposite sides.

Figure 5 is a detached view of the air-tube, so called.

Figure 6 is a detached view of the endless screw and its wheel.

Figure 7 is a detached view of a jewel-plate.

It has always been a serious objection to such lamps as make use of a train of mechanism, that the cost of such mechanism adds very much to the cost of the lamp, and thereby to a great degree prevents any very general use of such kind of lamps. In lamps employing or using such mechanism, and which are arranged and designed to burn kerosene and other similar oils, as are those lamps patented to said Caravan, it is particularly desirable to reduce the cost of construction as much as possible, so that such lamps can be brought within the reach of the community generally. My improvements have special reference to such end or purpose, and by their use the cost of construction of the mechanical movement, and consequently of the whole lamp, can be much reduced, and at the same time the action of the mechanism improved, and rendered more certain and uniform.

In the mechanical movements of such lamps, as heretofore constructed, the pinions α , with their arbors or spindles, have been made from a single piece of metal, the whole being reduced to proper shape and relative proportions in a lathe, and the leaves or teeth of the pinion cut by mechanism constructed for that purpose. Such construction is necessarily expensive. For pinions and arbors so constructed I employ pinions made from sheet brass, cut out by a suitable die, which can be done cheaply and rapidly, such pieces of brass which form the ends of the pinions being connected and fastened together by small steel wires, as seen in fig. 3, which wires form the leaves or teeth of the pinion, a central wire passing through the pinion forming the spindle or arbor. The use of such open or lantern-pinion greatly reduces the cost of this part of the mechanism, and renders available a pinion which clears itself, and requires but little if any cleaning.

The air-tube in such mechanism, or the short tube b , which contains the fan-blower, has heretofore been made up of a number of pieces, as the tube proper, the ears or projections by which it is connected with the side plates, and the cross-bar on top of such tube, which supports the upper end of the spindle of the fan-blower, and these have required to be fitted to each other, and then fastened by screws, &c. I form such tube, and all the said several parts, from one piece of metal, which can be struck out by a die from sheet metal, and which requires only to be bent into the form of a tube, and then soldered, and have its part c bent down to form the support for the upper end of the fan-spindle, when the tube is, as shown in fig. 5, ready for use.

The fan-spindle or endless screw, d , has heretofore been constructed with a thread having a double face, thereby requiring a wheel, which gears into it, with pointed and delicate teeth or cogs. Experience has proved, however carefully such screw and wheel may be constructed, that their action is liable to be imperfect. I overcome such defect by making the screw with a single thread, having vertical sides and a flat top, as shown in fig. 6, and combining with such screw, when so constructed, a wheel, e , with a square tooth adapted to gear into such screw. The action and operation of such screw and its operating-wheel are thus much improved, and rendered more uniform.

The plate or bridge c' , which forms the support of the lower end of the fan-spindle, or endless screw d , instead of being secured to the plate by one or more screws, as heretofore, is riveted thereto, as seen at o , figs. 2 and 3. Construction is thereby facilitated, and its cost reduced, and the connection between such bridge and the side plate of the mechanism is rendered more perfect and secure. The jewel-plates or straps n , which confine the jewels on which the spindle of the fan or the endless screw d runs, are made so that they are secured to the plates e e' by a single screw instead of by two or more, as heretofore, and the jewel-socket is simply a concave conical seat formed in such plates, as shown in fig. 7. Instead, also, of the use of a closed drum to contain the main or power-spring g , I make use of a simple band, f , which need be only sufficiently wide to confine the spring, so as to prevent it unduly expanding as it uncoils. Such band is riveted together with the main-spring hook or otherwise, and is also riveted to the main-spring wheel, thus avoiding soldering, as well as cheapening manufacture. Instead, also, of securing the ratchet k upon the arbor h in the usual manner, by means of a pin passing through such arbor, and having also an independent fastening for the click l , I confine both the ratchet and click, and hold them in their proper relative position by means of the click-plate m , which is secured by the same screw which fastens the click, and such plate, by passing over the arbor h , serves to strengthen and stiffen it. Such arrangement also facilitates the removal of the several parts when necessary.

By these improvements the several parts of the mechanism are rendered firmer and stronger, their action is rendered more uniform and certain, and the cost of the construction of the whole is very much reduced.

What I claim as my invention, and desire to secure by Letters Patent, is—

1. In a train or mechanism designed for use in lamps, the application and use of the open or lantern-pinion and its arbor, constructed substantially as and for the purposes set forth.
2. In such mechanism the combination of a single-thread, flat-top, solid-cut screw, with a square-toothed wheel, arranged and operating substantially as described.
3. The air-tube, constructed from a single piece of metal, substantially as and for the purposes set forth.
4. In combination with the endless screw d , attaching its lower support or bridge c' to the side plate of the mechanism, substantially as and for the purpose set forth.
5. The construction of the jewel-plates, having a concave conical jewel-seat, and confined to the supporting-plates by a single screw, substantially as and for the purposes set forth.
6. A mechanical movement for lamps, its several parts constructed and arranged and operating substantially as described.

GEO. A. JONES.
